WASHING MACHINE

William V. Orr, Cleveland Heights, Ohio, assignor
to The Apex Electrical Manufacturing Company, Cleveland, Ohio, a corporation of Ohio

Application July 15, 1929, Serial No. 378,273

4 Claims. (Cl. 74—78)

This invention relates to washing machines and has for its object the provision of a simple and compact washing machine of the oscillating-dasher and swinging-wringer type, which can be made readily and cheaply by large-scale production methods; which can be easily assembled; wherein the operating mechanism can be tested and adjusted before the addition of the tub and its appurtenances; wherein a new and improved arrangement shall be provided for driving the wringer; while further objects and advantages of the invention will become apparent as the description proceeds.

In the drawing I have shown an illustrative embodiment of my invention wherein Fig. 1 is a side elevation of a complete washing machine, partly in section, containing my improvements; Fig. 2 is a vertical sectional view through the working parts of Fig. 1 drawn to enlarged scale; and Fig. 3 is a horizontal sectional view taken on the line 3—3 of Figs. 1 and 2.

My improved washing machine is of the type comprising an upright tub 1 having in its bottom 2 an upright rock-shaft 3 carrying a suitable dasher 4 which is oscillated vigorously by a suitable mechanism; and also having an upright pillar 5 at one side carrying at its upper end a suitable wringer 6 mounted on a swinging joint at 7 so as to be adjustable about a vertical axis, and operable in either direction at any position by mechanism controlled by a suitable handle 8. In the present embodiment the tub 1 is located on top of a lower casing 10 in which is housed the motor 11 and gear-box 12. According to my invention this gear box consists of an elongated pan having a substantially horizontal bottom 13 and integral side-walls 14, 14, the latter terminating at the top in a sealing-flange 15. By means of suitable ears 16, 16 three in number this box is fastened to the top flange 17 of the bottom casing 10 and after the gearing devices have been installed therein, it is capped with a rigid cover 18 tightly bolted thereto. Formed in the bottom plate 13 beneath the center of the tub is a vertical aperture 19 concentric with which there is formed in the cap 18 an opening 20 to which is bolted a plate 21 having integral therewith a packing-box 22. Formed at the upper end of this box is a flange 23 surrounding an externally-threaded shoulder 24. The bottom 2 of the tub is formed at its center with an elevated portion 25, apertured for the reception of the shoulder 24 to which is then applied a nut 26 by which the parts are closely bound together, the tub held in place and leakage prevented. Threaded into the

top of the packing box 22 is a gland-nut 27 and journaled inside this box and traversing the gear-box 12 is the vertical rock-shaft 3 to which the dasher 4 is removably applied.

Formed in the bottom wall of the plate 13 just outside the outline of the tub 1 is a vertical cylindrical socket 30, the cover 18 being formed with a companion larger socket 31 above and coaxial therewith. Journaled in these sockets is a hollow sleeve 32, having an enlarged end 33 located in the upper socket, and surrounded just below the enlargement by an eccentric 34 which is tightly keyed thereto. Embracing this eccentric is a yoke 35, held in place by a flat circular plate 36 fastened to the bottom of the eccentric. Projecting horizontally from this yoke is a toothed rack 37 meshing with a pinion 38 carried by the shaft 3 and held in meshing-engagement with said pinion by means of a suitable stirrup 39. In the present embodiment this stirrup is pivoted on a kind of cage 40 surrounding the shaft and having a neck 41 projecting through the aperture 19 to enable adjustment from the outside.

The socket 30 terminates below in a reduced journal-bearing 42 and the socket 31 terminates above in a reduced journal-bearing 43 in which bearings are rotatably mounted the upright shaft 44 which project loosely and freely through the bore of the sleeve 33 so that the sleeve has its bearing entirely on its exterior. Slidably splined on the shaft 44 inside the socket 31 above this sleeve is a clutch-spool 45 operated by a shifting handle 46 mounted in the wall of the socket and formed with clutch-teeth 47 adapted to engage notches formed therefore in the enlarged end 33 of the sleeve. Secured to the upper end of the shaft 44 by means of a universal joint 48 is the drive-shaft 49 which operates the wringer and is housed in the pillar 5. Tightly secured to the lower end of the shaft 44 is a worm gear 50 meshing with a worm 51 carried by the horizontal shaft 52 provided with the belt-wheel 53 which is driven from the motor 11 by the belt 54. The bottom face 13 of the gear-box is formed with a depending skirt 55 to which is attached the oil-pan 56 surrounding this worm and worm-gear. Oil for the latter is introduced by removing the screw 57. The worm always runs in oil which also lubricates the lower bearings of the shaft 44. Due to its pan-like construction the box 12 can be packed with a large quantity of grease sufficient to last for years. An oil-hole 58 at the lower end of the pillar serves to lubricate the bearing 43 and any excess at this point merely runs into the gear-box and any excessive amount of oil in the worm 55

gear compartment of the gear-box is returned to the upper compartment thereof during the operation of the machine by way of the helical groove cut in the shaft 44. All the gearing is introduced 5 and adjusted before the tub is applied. Due to the way the eccentric is mounted, large tolerances are permissible, and all parts are readily interchangeable so that the machine is cheap to make, sure to work, and proof against getting out of order. Owing to the complete housing of the working parts children cannot be injured, and noise is avoided. The machine is free from the fault of getting oil on the floor, yet the parts are readily accessible in case of need. It will be 10 understood, however, that many changes in details can be made and I do not limit myself except as recited in my several claims.

Having thus described my invention what I claim is:

- 20 1. In a washing machine mechanism, in combination, a gear-box, a hollow sleeve traversing the same and journaled in the walls thereof, an eccentric surrounding and fastened to said sleeve, a shaft journaled in said gear-box independently of said sleeve and passing loosely therethrough, a rack operatively connected to said eccentric, a driving element for said shaft, and means for coupling said shaft to said sleeve in rotating relation.
- 25 2. In a washing machine mechanism, in combination, a lubricant retaining gear-box, a hollow sleeve traversing the same and journaled in the walls thereof, an eccentric surrounding and fastened to said sleeve, a shaft journaled in said gear-box independently of said sleeve and loosely 30 passing therethrough, oscillatory gearing operatively connected to said eccentric, a driving ele-

ment for said shaft, means associated with said shaft for supplying lubricant to said hollow sleeve during the operation of the shaft, and means for coupling said shaft to said sleeve in rotating relation.

3. In a washing machine mechanism, in combination, a lubricant retaining gear-box having a partition wall dividing the same into upper and lower compartments, a hollow sleeve journaled in the walls of said gear-box, an eccentric surrounding and fastened to said sleeve, a shaft journaled in said gear-box independently of said sleeve and passing loosely therethrough, oscillatory gearing operatively connected to said eccentric, driving means for said shaft, means associated with said shaft operative during the rotation thereof for transferring lubricant from one compartment to the other of said gear-box, and means for coupling said shaft to said sleeve in rotating relation.

4. In a washing machine mechanism, in combination, a lubricant retaining gear-box having a partition wall dividing the same into upper and lower compartments, a hollow sleeve journaled in the walls of said gear-box, an eccentric surrounding and fastened to said sleeve, a shaft journaled in said gear-box independently of said sleeve and passing loosely therethrough, oscillatory gearing operatively connected to said eccentric, driving means for said shaft, means associated with said shaft operative during the rotation thereof for transferring lubricant from the lower to the upper compartment of said gear-box, and means for coupling said shaft to said sleeve in rotating relation.
